TOOL RETAINER

Earl B. Lear and Alfred G. Slatcher, Detroit,
Mich., assignors to Chicago Pneumatic Tool
Company, New York, N. Y., a corporation of
New Jersey

Application August 5, 1937, Serial No. 157,508

8 Claims. (Cl. 121—32)

This invention relates to retainers for percussive tools and more particularly to a drill steel retainer for a rock drill of the hammer type.

An object of the invention is the provision of a retainer that can be swung into and out of operative relation to the drill steel with minimum effort on the part of the operator.

Another object is the provision of a retainer in which the parts that are subject to wear or breakage are relatively inexpensive.

A feature of the invention resides in an arrangement for mounting the trunnion bearings in communication with the chuck chamber so that the bearings will be automatically lubricated.

Other objects and features of the invention will be apparent from the following description taken in connection with the accompanying drawing and appended claims.

In the accompanying drawing, which illustrates two embodiments of the invention;

Fig. 1 is a front view partly in elevation, and partly in section, of a rock drill embodying the invention;

Fig. 2 is a side elevation of the device shown in Fig. 1;

Fig. 3 is a cross section as indicated by the broken line 3—3 in Fig. 1;

Fig. 4 is a section as indicated by the arrows 4 in Fig. 1;

Fig. 5 is a perspective view, on an enlarged scale, of one of the trunnion washers;

Fig. 6 is a fragmentary view, similar to Fig. 1, illustrating a modification;

Fig. 7 is a plan view of the modified trunnion washer on an enlarged scale; and

Fig. 8 is a longitudinal section of the trunnion washer on the same scale as Fig. 7.

Referring to the embodiment illustrated in Figs. 1 to 5 inclusive, a drill steel 10 is provided with a collar 11 engaging the lower end of a chuck 12 mounted in a bore 13 in the front head 14 of a rock drill. Shank 15 of the steel is of polygonal cross section and has a sliding fit with the chuck. The upper end of the shank is adapted to receive blows delivered by a piston (not shown).

Front head 14 has a pair of aligned transverse bores 16 extending inwardly from a pair of bosses 17 at opposite sides of the front head. Each bore 16 provides a socket for receiving a trunnion bushing 18. The bushing has a hollow stem which fits the bore 16 and a flange 19 which seats against a flat surface on boss 17. The bushings 18 are held in their respective sockets by a press fit and are adapted to be removed and replaced after they have become worn. In order to prevent the

bushings from turning, flanges 19 are provided with non-circular or flattened portions 20 adapted to seat on lugs 21 projecting from and integral with the front head. A pair of trunnions 22 are provided with pivot portions 23 mounted to turn in the bushings 18.

A tool retainer member 24 has a yoke portion 25 of ordinary construction adapted to underlie the collar 11 on the drill steel 10 and a pair of upstanding substantially parallel arms 26. The arms 26 have cylindrical extensions 27 slidably fitting bores in the trunnions 22 and have collars 28 seating against the lower ends of the trunnions. The upper extremities of the arms 26 are provided with removable securing means such as nuts 29. Compression springs 30 surround the extensions 27 and abut against the nuts 29 to support the retainer in its uppermost position with the collars 28 seated on the trunnions.

The trunnions 22 and retainer member 24 are yieldingly locked in adjusted position by means of trunnion washers 31 surrounding the extensions 27 on the retainer member. Each washer has a flange or key portion 32 at one end which seats on a shoulder at the outer side of the associated trunnion 22. The other end of the washer seats on one of the camming or flat faces 33 on the edge of the bushing flange 19. Washer 31 is held in firm contact with the trunnion shoulder and the bushing flange by spring 30. The bore in the washer is slightly larger than the diameter of extension 27 to permit the washer to tilt as it moves from one flat face 33 to another.

In operation, the drill steel 10 is subjected to impacts delivered by a hammer piston (not shown) and, under certain conditions, may strike against the yoke portion 25 of the retainer member 24. Springs 30 act as a shock absorber by permitting the retainer member to yield in the direction of the impacts. This action minimizes wear on the front head and prolongs the life of the parts of the retainer. The retainer member is normally held in the position shown in full lines in Fig. 2. When it is desired to change drill steels, the retainer member is swung to the broken line position. Movement away from the adjusted position is resisted by the pressure of the trunnion washer 31 against the camming edge of bushing flange 19. As the retainer member 24 swings, it carries with it the trunnions 22 and trunnion washers 31, the latter riding over the edges separating the flat faces 33 on the bushings 18. The key portions 32 of the trunnion washers serve two functions: First to prevent rotation of the washer about its own axis; and second to act as a fulcrum

for the washer as it tilts in response to the camming action of the bushing flange 19.

In accordance with usual practice, lubricating oil is supplied between chuck 12 and front head 14. The oil is free to pass through the bores 16 to the trunnion bushings 18, thereby facilitating pivotal movement of the trunnions 22.

In the embodiment illustrated in Figs. 6, 7 and 8, the construction of the front head 14, drill 10 steel 10, retainer member 24 and bushings 18 is the same as that of the corresponding parts in the embodiment first described. Trunnions 34 are similar to trunnions 22 but have bores of larger diameter than the retainer member extensions 27. Trunnion washer 35 has a sleeve portion 36 which is in telescoping relation to both the extensions 27 and the bore of the trunnion 34. A flange 37 is formed at the upper end of the sleeve and is adapted to seat on the edge of bushing flange 19 which is provided with flat or camming faces 33, shown best in Fig. 4. Spring 38 holds the washer 35 in engagement with the edge of bushing flange 19. While Fig. 6 shows the bushing and washer arrangement supporting only one arm of the retainer member 24, it will be understood that a similar arrangement may be employed for supporting the other arm.

The operation of the modified tool retainer is generally similar to that of the embodiment illustrated in Figs. 1 to 5 inclusive, the principal difference being that the trunnion washer 35 can move only in the direction of the axis of the retainer member extensions 27 whereas trunnion washer 31 rocks about the fulcrum portion 32.

Further description is deemed unnecessary.

It will be apparent that various changes and adaptations of the illustrative embodiment of the invention may be resorted to without departing from the spirit of the invention or the scope of the claims. For example, one arm of the retainer member 24 may be supported as shown in Fig. 1 and the other arm supported by the modified arrangement of Fig. 6. Furthermore, the "front head" referred to in the specification and claims need not necessarily be in one piece but may comprise several parts carried by the cylinder either in fixed relation or so connected relative thereto as to accomplish the results obtained by the illustrative embodiments of the invention.

What is claimed is:

1. In combination with a front head and a collared working tool supported therein, a retainer member having a yoke portion adapted to underlie the collar and having parallel arms extending upwardly therefrom along opposite sides of the front head, said front head having a pair of axially aligned transverse bores, a pair of trunnions mounted for turning movement in said bores, said trunnions having bores in which the retainer member arms are mounted for sliding movement, means limiting sliding movement of the arms relative to the trunnions and releasable means for locking the trunnions against pivotal movement relative to the front head, said locking means comprising a washer surrounding one of the arms of the retainer member, and a cam element fixed to the front head, said washer being held in engagement with said cam element.

2. In the combination set forth in claim 1, said washer and its associated trunnion having inter-engaging means for preventing rotation of the washer about the axis of the associated retainer member arm.

3. In combination with a front head and a

collared working tool supported therein, a retainer member having a yoke portion adapted to underlie the collar and having parallel arms extending upwardly therefrom along opposite sides of the front head, said front head having a pair of axially aligned transverse bores, a pair of trunnions mounted for turning movement in said bores, said trunnions having bores in which the retainer member arms are mounted for sliding movement, means limiting sliding movement of the arms relative to the trunnions and releasable means for locking the trunnions against pivotal movement relative to the front head, said locking means comprising a washer surrounding one of the arms of the retainer member, a stationary element carried by the front head and having a flat portion facing said washer, and a spring holding the washer in engagement with the flat portion of said element.

4. A rock drill comprising a front head and a collared drill steel supported therein, a retainer member having a yoke portion normally underlying the collar and having arms extending upwardly on opposite sides of the front head, said front head having a pair of aligned transverse bores, a pair of renewable bushings mounted in said bores and held therein by a press fit, each bushing having a flange seated against the side of the front head, a pair of axially aligned trunnions mounted to turn in said bushings and removable from the front head by movement away from each other, each trunnion having a bore in line with and receiving an arm of the retainer member, whereby said retainer member normally prevents removal of the trunnions from the front head, said arms having a sliding fit with the trunnions, removable members secured to the free ends of the arms, springs between said last-mentioned members and the trunnions for resiliently supporting said arms and means yieldingly resisting locking movement of the trunnions and arms away from the normal position, said means comprising a cam surface on the peripheral edge of one of the bushings and a washer interposed between the spring and the trunnion associated with the last-mentioned bushing, said washer being held in contact with said cam surface by means of said spring.

5. A rock drill comprising a front head, a collared working tool supported therein, a retainer member for said tool having a yoke portion adapted to underlie the collar and having parallel arms extending upwardly along opposite sides of the front head, said front head having a pair of axially aligned transverse bores, a pair of renewable bushings supported in said bores and held against movement relative to the front head, a pair of trunnions mounted for turning movement in said bushings, said trunnions having bores in which the retainer member arms are mounted for longitudinal movement, a spring surrounding each arm, removable means attached to the upper ends of the arms and resting on the springs to provide a resilient support for the retainer member, a washer interposed between the lower end of one of the springs and the associated trunnion, the associated bushing having a non-circular peripheral surface, said washer being forced into engagement with said non-circular surface to resist pivotal movement of the trunnions.

6. A rock drill according to claim 5 in which the trunnion associated with said washer has a shoulder at its outer end and the washer has a fulcrum portion resting on said shoulder whereby the washer may tilt in opposition to spring

pressure as it is carried over the non-circular surface.

7. A rock drill according to claim 5 in which said washer has a sleeve portion interposed between and having a telescopic fit with both the trunnion and the arm associated therewith.

8. A rock drill comprising a front head, a collared working tool supported therein, a retainer member for said tool having a yoke portion adapted to underlie the collar and having parallel arms extending upwardly along opposite sides of the front head, said front head having a pair of axially aligned transverse bores, a pair of renewable bushings supported in said bores and held against movement relative to the front head, a pair of trunnions mounted for turning movement in said bushings, said trunnions having

bores in which the retainer member arms are mounted for longitudinal movement, a spring surrounding each arm, removable means attached to the upper ends of the arms and resting on the springs to provide a resilient support for the retainer member, a washer interposed between the lower end of one of the springs and the associated trunnion, the associated bushing having an exposed portion extending beyond the side of the front head, said exposed portion having a plurality of flat surfaces on its periphery, said washer being held by the spring in engagement with any one of said flat surfaces to resist pivotal movement of the trunnions away from their selected position of adjustment. 10
